DESIGN FOR A SAILBOAT SHELF FIGURE

Eugene R. Bartolomeo, Waterbury, Conn.

Application May 10, 1947, Serial No. 138,973

Term of patent 7 years

(Cl. D33—3)

To all whom it may concern:

Be it known that I, Eugene R. Bartolomeo, a citizen of the United States, residing in Waterbury, county of New Haven, and State of Connecticut, have invented a new, original, and ornamental Design for a Sailboat Shelf Figure, of which the following is a specification, reference being had to the accompanying drawing, constituting a part thereof.

Fig. 1 is an end elevational view of a sailboat shelf figure, showing my new design.

Fig. 2 is a front elevational view of the sailboat shelf figure shown in Fig. 1.

Fig. 3 is a top plan view thereof.

I claim:

The ornamental design for a sailboat shelf figure, substantially as shown.

EUGENE R. BARTOLOMEO.
